Specification for Design.

Patented Aug. 19, 1919.

Application filed January 20, 1915. Serial No. 3,420. Term of patent 3½ years.

To all whom it may concern:

Be it known that I, HARRISON HURLBERT BOYCE, a citizen of the United States, residing at Forest Hills, in the county of Queens and State of New York, have invented a new, original, and ornamental Design for a Casing for Signal-Horns, of which the following is a specification, reference being had to the accompanying drawings, forming a part thereof.

Referring to the annexed sheet of drawings, Figure 1 represents a side elevation of a design for a casing for signal horns, made

in accordance with my invention, and Fig. 2 is a rear view thereof.

I claim:

The ornamental design for a casing for signal horns as shown.

In witness whereof I have hereunto set my hand, in the presence of two subscribing witnesses, this 18th day of January, 1915.

HARRISON HURLBERT BOYCE.
